UNITED STATES PATENT OFFICE.

WILLIAM C. HAKE, OF ST. LOUIS, MISSOURI.

SEWING MACHINE.

Application filed April 8, 1925. Serial No. 21,505.

This invention relates to improvements in sewing machines, and more particularly to an attachment for feeding a tape to form a French binding for shoes.

5 An object of the invention is to provide an attachment whereby tape of varying width may be fed to the sewing mechanism of a sewing machine for attaching the same to the marginal edges of shoe uppers to 10 form a French binding.

Additional advantages of the construction will be apparent from the following detailed description thereof taken in connection with the accompanying drawing, in which

15 Fig. 1 is a rear elevation of the attachment and associated parts.

Fig. 2 is an end view.

Fig. 3 is a front elevation.

Fig. 4 is a broken section.

20 Fig. 5 illustrates a portion of a shoe upper with a tape attached to the marginal edge thereof.

Fig. 6 is an end view of the binder feed tube.

25 In the embodiment of the invention illustrated in the drawing the attachment is shown in association with a sewing machine having a top arm 1 shown fragmentarily in the drawing, in which there is a reciprocating needle bar 2 carrying a needle 3. The top arm 1 carries a rigid support 4 for a presser roller bracket 5, said bracket being disposed in a vertical position and removably supporting near its lower end a 30 roller arm 6. The roller shaft, which is in the form of a screw bolt 7, extends through the lower end of the arm 6 to which it is secured by a nut 8 in such manner that the roller presser wheel 9 tilts backwardly, as 35 illustrated in the drawing. The roller presser wheel has a knurled periphery 10 and a hub 11, said wheel being revolvably mounted upon the rigid shaft 7. The forward face 12 of the wheel 9 is concave so that when 40 the tape is fed forwardly against said face 12 the marginal edge of the face of the wheel 9 tends to turn the lower edge of the tape to a horizontal position so as to receive a 45 stitch from the needle.

50 The flat piece of material 13, to the marginal edges of which the tape is attached, is fed forwardly between the periphery of the wheel 9 and the feed plate 14 of the sewing machine and is so positioned that the marginal edge thereof projects slightly 55 beyond the edge of the roller presser wheel 9.

The attachment for feeding the tape includes a downwardly curved arm 15 removably attached to the roller presser bracket 5 by a screw 16 operating in a slot 17. At 60 the back of the arm 15 is a curved guide plate 18 having a loop 19 at its extremity through which the tape is threaded. Extending forwardly and downwardly from the front of the arm 15 is a binder feed tube 20, which tube is formed from flattened spaced walls providing an upper throat 21 the edge of which inclines downwardly and the vertical dimension of which is such that it is adapted to receive a tape of the maximum width. The tube 20 is so supported that it inclines inwardly toward the face 12 of the roller presser wheel 9, the lower marginal edge of the tube being turned out at 22 to form a deflecting surface for the lower 70 marginal edge of the tape, thereby feeding the tape against the material to which it is to be stitched in substantially a horizontal plane with the face of such material. The upper edge of the lower portion of the tube is slightly deflected outwardly at 23 and the vertical dimension of the lower throat of the tube is less than the vertical dimension of the opposite throat so that when tape of the maximum width is fed 80 through the tube the upper edge thereof will be turned outwardly forcing the lower marginal edge of the tape to the lower wall of the tube, so that it will be guided as it is presented to the material to which it is to be 85 stitched in substantially a horizontal plane. The variation between the vertical dimension of the inlet end of the tube and the outlet end of the tube is substantially 90 the variation between the various widths of 95 tape with which the feeding device is adapted to operate.

By the use of the attachment the tape may be fed for stitching operation on all classes of shoe uppers where sharp curves 100 or angles in the direction of the stitching is required without lapping or wrinkling the tape in any manner.

I am aware that the invention may be varied in various particulars without departing from the spirit and scope thereof. I do not limit myself therefore to unessential details but what I claim and desire to secure by Letters Patent is:—

1. In a sewing machine, the combination 110 with stitching and feeding mechanism, said feeding mechanism including a presser roll-

- er having a concave outer face; of an attachment adapted to feed the margin of a tape to the stitching point comprising a guideway having a vertical portion and an 5 out-turned portion, said guideway being arranged adjacent to the concave face of the roller, and said guideway having a delivery throat, the vertical portion of said guideway being disposed inwardly of the outer 10 plane of the roller and the lower marginal edge of said out-turned portion of the guideway extending outwardly from the plane of the roller, whereby the outer marginal edge of the tape is fed to the stitching point 15 in substantially a horizontal position;
2. In a sewing machine, the combination with stitching mechanism, of a flat feed mechanism for the material, said feed mechanism including a presser roller having a 20 concave outer face, a removable attachment for feeding tape including an arm, a guide plate, and a tape feeding tube, the delivery end of said tube disposed within the concave portion of the feed roller and the lower 25 marginal edge of the throat of the delivery end of said tube being deflected outwardly.

in substantially a horizontal plane, whereby the outer marginal edge of the tape is presented to the stitching point adjacent to the outer edge of the feed roller, said feeding 30 throat coacting with the concave face of the roller to turn the lower marginal edge of the tape outwardly.

3. In a sewing machine, the combination with stitching mechanism and feeding 35 mechanism for the material, of a tape feeding guide tube having a vertical portion and an outwardly curved throat presenting a marginal edge of the tape along the line of stitching substantially parallel with the 40 face of the material to which the tape is attached and said tube tapering downwardly in width and the throat of said tube having an outwardly turned upper portion and a lip formed internally of said curved portion, whereby downward pressure is exerted on the upper marginal edge of the tape passing through said guide tube to hold the lower marginal edge of the tape close against the curved lower marginal edge of the delivery 45 throat thereof.

WILLIAM C. HAKE.
